AMUSEMENT DRIVING DEVICE

Ralph Hotkins and Charles Shankman, Brooklyn, N.Y.,
assignors to Capitol Projector Corp., New York, N.Y.,
a corporation of New York

Filed Aug. 20, 1962, Ser. No. 71,360

Term of patent 7 years

(Cl. D25—1)

Fig. 1

Fig. 2

Fig. 3

Fig. 4

Fig. 5

FIGURE 1 is a view in perspective of an amusement driving device showing our new design;

FIGURE 2 is a side elevational view thereof;

FIGURE 3 is a front elevational view thereof;

FIGURE 4 is a rear elevational view thereof; and

FIGURE 5 is a plan view thereof.

We claim:

The ornamental design for an amusement driving device, substantially as shown.
